UNITED STATES PATENT OFFICE.

CHARLES A. HANEY, OF BROOKLYN, NEW YORK.

DESIGN FOR A CYCLOMETER-CASE.

SPECIFICATION forming part of Design No. 28,079, dated December 21, 1897.

Application filed November 8, 1897. Serial No. 657,883. Term of patent 7 years.

To all whom it may concern:

Be it known that I, CHARLES A. HANEY, a citizen of the United States, residing at Brooklyn in the county of Kings and State of New York, have invented and produced a new and original Design for a Cyclometer-Case, of which the following is a specification, reference being had to the accompanying drawings, in which—

10 Figure 1 is a perspective view. Fig. 2 is an elevation; Fig. 3, a plan, and Fig. 4 an end view in larger size.

15 The leading features of my design consist of a cylindrical body and a semicylindrical downward enlargement at one end.

The portion *a* of the case is cylindrical, with

a flat end *b*, and the upper part of the case continues to the other flat end *c*, and there is a downward extension *d* that is semicylindrical, the connecting portions 2 2 being flat, and the flat portion *e* connects with the cylindrical part *a*. There is an opening at *f*.

What I claim is—

The design for a cyclometer-case, substantially as shown and described. 25

Signed by me this 14th day of September, A. D. 1897.

CHAS. A. HANEY.
